TEMPLE FOR AN EYEGLASS FRAME

Herman Goodman, New York, N. Y., assignor to Zylite Products Co., Inc., New York, N. Y., a corporation of New York

Application May 29, 1957, Serial No. 46,394

Term of patent 7 years

(Cl. D57—1)

Fig. 2.

Fig. 1.

Fig. 3. Fig. 4.

Fig. 1 is a side elevational view of a left temple for an eyeglass frame, embodying my new design;

Fig. 2 is an enlarged top plan view of Fig. 1;

Fig. 3 is a cross sectional view thereof taken on the line 3—3 of Fig. 1, and

Fig. 4 is a cross sectional view thereof taken on the line 4—4 of Fig. 1.

I claim:

The ornamental design for a temple for an eyeglass frame, substantially as shown.
